(57) **CLAIM**

The ornamental design for X-shaped music stand, as shown and described.

DESCRIPTION

FIG. 1 is a perspective view of a x-shaped music stand showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and the left side being a mirror image;

FIG. 7 is a cross sectional view taken along line 7-7 in FIG. 2;

FIG. 8 is a cross sectional view taken along line 8-8 in FIG. 3; and,

FIG. 9 is a cross sectional view taken along line 9-9 in FIG. 4. Those portions of the design indicated by broken lines form no part of the claimed design.
